UNITED STATES PATENT OFFICE

DONALD S. BARROWS, OF ROCHESTER, NEW YORK, AND BYERS W. KADEL, OF BALTIMORE, MARYLAND, ASSIGNORS TO THE SYMINGTON COMPANY, OF NEW YORK, N. Y., A CORPORATION OF MARYLAND

SIDE FRAME

Application filed February 14, 1929. Serial No. 339,906.

This invention relates to side frames for railway car trucks and, more particularly, to strengthening the connection between said frames and journal boxes integrally formed therewith.

The principal object of our invention, generally considered, is to improve the general appearance of cast steel side frames with integral journal boxes and eliminate the separate core heretofore used at the junction between the journal boxes and side frames and improve the strength of connection between such frames and their journal boxes.

Another object of our invention is to improve the connection between integral journal boxes and their associated frames by downwardly convoluting the web of the tension member of the frame to provide a hollow bracket between said member and the adjacent side wall of the box, the lower edge of said bracket being preferably curved and the side walls flaring upwardly and outwardly but maintained of a width less than the distance between the flanges of the tension member.

A further object of our invention is to provide a side frame with integral journal boxes, the roofs of said boxes being preferably beveled rearwardly of the front flange of the tension member with the web of the tension member forming, in effect, a continuation of the corresponding beveled portion of the journal box roof, the connection between the tension member and journal box being reinforced by an integral pending convolution of rounded triangular form maintained of less width than the tension member web with the remainder of the web extended to directly join the roof of the box, said roof at the junction being of increased thickness and gradually tapering to normal thickness at the other side of the box for efficiently distributing forces from the tension member to the roof of the box.

A still further object of our invention is to provide a side frame and integral journal box construction in which the connection with the box is rigidified, and the formerly used separate core obviated, by a depending hollow corrugation in the web of the tension member of

less width than said web, the remaining portions of said web being flared outwardly beyond the flanges of said tension member and united with the roof of the box.

Other objects and advantages of the invention relating to the particular arrangement and construction of the various parts will become apparent as the description proceeds.

Referring to the drawings illustrating our invention, the scope whereof is defined by the appended claims.

Figure 1 is a fragmentary sectional view of one end of a side frame and integral journal box embodying our invention, said section being taken on the line 1—1 of Figure 3 looking in the direction of the arrows.

Figure 2 is a fragmentary transverse sectional view on the line 2—2 of Figure 1 looking in the direction of the arrows.

Figure 3 is a horizontal sectional view on the line 3—3 of Figure 1 looking in the direction of the arrows.

Figure 4 is a longitudinal sectional view on the line 4—4 of Figure 3 looking in the direction of the arrows.

Figure 5 is a fragmentary end view of the frame and associated journal box particularly showing the construction of the brass lug.

Figure 6 is a fragmentary sectional view corresponding to Figure 1 showing the junction between the tension member of the frame and journal box in perspective.

Referring to the drawings in detail, like parts being designated by like reference characters, there is shown a side frame 1 of the cast type comprising a tension member 2 and a compression member 3 uniting at their ends and to integral journal boxes 4, only one of which is illustrated. Although only a fragmentary portion of the frame is shown, it will be understood that the construction is an improvement of the type of frame illustrated and described in the Hankins Patent No. 1,637,696 of August 2, 1927, and said frame has a compression member and a tension member spaced at intermediate portions by struts or bolster guide columns, the tension and compression members converging at their ends and united together and to integral journal boxes. Inasmuch, however, as the

portions of the frame not illustrated are of well known construction, it is not deemed necessary to show any more than just the novel features which will now be pointed out.

5 In the Hankins patent heretofore referred to, the connection between the tension member and journal box was reinforced by a pair of web portions spaced from the junction between the web of the tension member and box 10 and from each other, thereby necessitating a separate core. In the present case, the connection between the tension member 2, which is preferably channel shape in cross section and comprises a lower web 5 and upstanding 15 flanges 6 and the journal box 4 is reinforced by a bracket 7 of hollow rounded triangular form preferably constructed as a convolution or depending corrugation in the web 5 of the tension member 2. Said bracket 7 is preferably 20 of less width than the web 5 of the tension member and the lower edge thereof is preferably rounded, as indicated at 8, and of approximately semi-circular form, the sides 9 being preferably thinner than the 25 curved portion 8 and flaring outwardly and upwardly to join with the remaining portion 10 of the web 5 of the tension member, which portion is preferably thickened as illustrated particularly in Figure 2, to compensate for 30 the convolution in said web, and continued outwardly and upwardly to join with the roof 11 of the box preferably at the junction with the inner or adjacent brass lug 12. Said roof at the junction with the thickened web 10 of 35 the tension member is preferably of corresponding thickness, as indicated at 13, and tapers outwardly from a maximum to normal width adjacent the other side of the box, as shown most clearly in Figure 1.

40 The journal box is preferably beveled at its upper corners rearwardly of the front flange 6 of the tension member, said beveling being preferably produced by sloping the roof of said box downwardly and outwardly from 45 the planes of the inner walls of the brass lugs 12 and 14, said slope preferably corresponding with the general inclination of the web 5 of the tension member 2 so that said tension 50 member forms in effect a continuation of the sloping portion of the roof at the adjacent side walls of the box.

For further reinforcing the connection between the frame 1 or the tension member 2 55 thereof and the journal box 4, the web 5 of the tension member is preferably flared beyond the flanges 6 to provide a forward tapering transverse gusset 15 and a rearward tapering transverse gusset 16, the forward gusset preferably 60 extending slightly above the adjacent portion of the web 5 so as to join with the corner of the box outwardly of the front flange of the tension member which is not beveled, the gusset 16, however, preferably 65 being extended in the plane of the web 5,

although of normal thickness rather than increased in thickness as shown most clearly in Figure 2, so that it joins with the beveled roof portion 17 of the box rearwardly of the rear flange 6 of the tension member.

70 The brass lugs 12 and 14 are of normally less width than the tension member 2 or the distance between the flanges 6 thereof, but for increasing the strength of the box and the connection with the frame as well as improving the appearance, the walls 18 and 19 of said brass lugs are preferably flared outwardly and upwardly as shown particularly in Figure 5 for the brass lug 14. The lug 12 is preferably 75 made of similar contour so that the green sand core used in making the journal box may be symmetrical and the same at both ends of the frame. On account of the beveling of the roof of the box, a similar beveling occurs at the upper ends of the brass lugs as indicated particularly at 20 and 21, the beveling at 20 being slightly less than that at 21 because of the reduced width of the forward portion of the box.

80 From the foregoing description taken in connection with the accompanying drawing, it will be seen that we have improved the construction, strength and general appearance of cast side frames with integral journal boxes by reinforcing the connection between the tension member and box, by means of a 85 bracket formed as an integral depending convolution or corrugation of rounded triangular form in the web of the tension member, the lower edge of said convolution preferably meeting the adjacent wall of the box at the bottom of the corresponding brass lug, said convolution or hollow connecting bracket being of a width generally less than the width 90 of the tension member and approximating that of the brass lugs, the sides of said bracket flaring upwardly and outwardly from a substantially semi-circular lower edge, and the brass lugs provided with walls flaring outwardly to approximately or slightly less than 95 the distance between the flanges of the tension member or the side walls of said frame at the junction between the tension and compression members. The inner contour of the brass lugs 100 is preferably uniform to make it possible to use symmetrical journal box cores, thereby 105 making the cores the same for both journal boxes, the outer contour, however, being necessarily different because of the junction with the tension member. The core for the reinforcing bracket and corresponding brass lug 110 is unitary with that for the tension member, thereby avoiding the separate core heretofore used for constructing the reinforcing web or webs between the bottom of the tension member and the adjacent side wall of the box. The tension member web on either side of the 115 reinforcing bracket or convolution is preferably thickened to compensate for the diver- 120 125 130

gence of the central portion of said web, and the roof of the journal box is correspondingly thickened and gradually tapered outwardly to normal thickness adjacent the other side of the box.

5 The remaining portion of the tension member web above the convolution or depending reinforcement therein is not only thickened towards its junction with the roof of the box, but is preferably extended laterally beyond the flanges of the member to provide transverse gussets of normal thickness between the sides of the tension member and the roof of the box at the junction with the inner side 10 wall thereof. Although a preferred embodiment of our invention is illustrated and described, it will be understood that modifications may be made therein within the spirit and scope of the appended claims.

15 Having now described our invention, we claim:

1. A truck side frame comprising a tension member, a compression member, said members united together at their ends, a journal 20 box with brass lugs integrally united to each end of the frame, said tension member being channel shape in cross section with the web of the channel sloping generally in the direction of the upper inner corner of the adjacent 25 brass lug, the connection between said tension member and journal box being rigidified by a hollow curved bracket formed as a downward convolution of the web of the tension member, said connection being further reinforced by gussets extending laterally beyond the flanges of the tension member and joining with the roof of the box.

2. A truck side frame comprising a tension member, a journal box with brass lugs integrally united to an end of said member, said tension member being channel shape in cross section with the web of the channel sloping generally in the direction of the upper inner corner of the adjacent brass lug, the connection between said tension member and box 40 being strengthened by a hollow bracket depending from the web of the tension member with the lower edge curved approximately semi-circular and the sides flaring outwardly 45 and upwardly to join with the normal web of the tension member.

3. A truck side frame comprising a tension member, a journal box with brass lugs integrally united to an end of said tension member, said member being channel shape in cross section, the roof of said journal box being beveled rearwardly of the front flange of the tension member from the transverse planes 55 of the inner sides of the brass lugs, the web of the tension member joining the roof of the journal box as a continuation of the corresponding beveled portion, the connection between the tension member and box being reinforced by a downward convolution in the 60 web of the tension member, said convolution

being of less width than said web with the lower edge thereof curved approximately semi-circular in cross section.

4. A truck side frame comprising a tension member, a journal box with brass lugs integrally united to an end of said member, said connection between the tension member and box being rigidified by a downward convolution in the web of the tension member approximately the width of the adjacent brass lug, the remaining portion of the tension member web being flared outwardly beyond the flanges to the adjacent portions of the roof of said box as external gussets.

5. A truck side frame comprising integrally formed tension and compression members and journal boxes at the ends of said members, said journal boxes having hollow inwardly extending brass lugs generally narrower than the width of the tension member with their side walls flared outwardly to approximately the width of said tension member, the inner surfaces of the brass lugs on opposite sides of the journal box being correspondingly formed to provide for a symmetrical journal box core.

6. A truck side frame comprising a tension member, a journal box with brass lugs integrally formed at an end of said member, said tension member having a lower web and upstanding flanges, said flanges being spaced a greater distance than the normal distance between the side walls of the brass lugs, the upper portions of said side walls flaring outwardly to approximately the width of the tension member, the roof of said box being beveled between the flanges of said tension member from the inner walls of the brass lugs downwardly and outwardly to correspond with the general slope of the tension member web at the junction between said tension member and journal box.

7. A truck side frame comprising a tension member, a journal box integrally united to the end of said member, said member having a lower web and upstanding flanges, said web joining the roof of the journal box, the thickness of said journal box roof at said junction being a maximum and gradually tapering outwardly therefrom to normal thickness at the outer side of said box.

In testimony whereof we affix our signatures.
